UNITED STATES PATENT OFFICE.

EDGAR LANGLEY FANDALL, OF MUSWELL HILL, ENGLAND, ASSIGNOR TO THE GENERAL ELECTRIC COMPANY LIMITED, OF LONDON, ENGLAND, A BRITISH COMPANY.

LIGHTING FITTING.

Application filed July 7, 1926, Serial No. 120,919, and in Great Britain March 31, 1926.

This invention relates to lighting fittings and more particularly to galleries for supporting glassware or the like, and is especially applicable to electric lighting fittings, the object of the invention being to provide an improved lighting fitting of simple construction which may be readily opened, by lowering a globe, shade, or the like, from the canopy covering an opening therein, to give access to the interior for inspection and cleaning without taking the fitting to pieces, and which may also be readily reclosed merely by raising the globe or the like to the canopy and which presents a neat and compact appearance, without unsightly working parts exterior to the canopy.

A lighting fitting accordance to the present invention comprises a compact unit including a canopy for covering an opening in the top of an illumination appliance such as a globe or the like, flexible means, a support for the said appliance connected to the flexible means, and contained within the canopy a member arranged to be rotated by hand in the one or the other direction about the axis of the lighting fitting, and adapted by such rotation to change the flexible means from the extended position to raise the support to the canopy, and to allow the flexible means to extend to lower the support.

The invention will now be described by way of example with reference to the accompanying drawings, in which Figure 1 is a half sectional side elevation of one embodiment of the invention, Figure 2 is a half sectional side elevation of another embodiment of the invention, and Figure 3 is a plan view of a supporting ring.

In the drawings glass globe 1 is supported by ring 2, which is held in position by two flexible plaited copper suspension wires 3. The fitting may be suspended by ring 4, screwed onto central spindle 5, and locked in position by screw 6.

In Figure 1 drum 7 is rigidly attached to cover 8, which forms the upper part of a canopy, and which is rotatable on spindle 5, that supports the lower part 9 of the canopy rigidly connected to two armed spider 10 screwed onto the spindle. The upper part of the spindle is also provided with threads for co-operating with locking nut 11, which is adapted to clamp cover 8 against positioning sleeve 12, thus securing drum 7 in position.

The upper ends of suspension wires 3 are secured in brass tubes 13, fastened to the upper part of drum 7, whilst the lower end of each suspension wire is passed through a hole 14 in a lug 15 of ring 2, and fitted with a cap 16 of such size that it will not pass through the hole, but will serve to support the ring. Each wire 3 is passed through an eyelet 21 in canopy 9, which eyelet serves to guide the wire as it is wound onto the drum 7.

When locking nut 11 is loosened, cover 8 may be rotated, thus unwinding wires 3 from drum 7, extending the wires, and lowering ring 2 and globe 1 from the raised position. When ring 2 is in the lowered position cover 8 may be rotated to change wires 3 from the extended position and wind them onto drum 7, thus raising ring 2, which may be locked in a raised or in an intermediate position by tightening up locking nut 11.

In Figure 2 lower part 9 of the canopy is secured to a three armed spider 17, which screws onto the upper part of spindle 5, whilst cover 8 forming the upper part of the canopy is clamped between spider 17 and ring 4.

The part 9 of the canopy is provided with an annular downwardly projecting flange 18, and with hoop 19, rigidly secured to the part 9, and formed in such a way that it retains lip 20 of canopy 9 but allows rotation of the lip relative to the canopy. The upper ends of suspension wires 3 are secured in brass tubes 13 fastened to the lower part 9 of the canopy, whilst the lower end of each suspension wire is passed through a hole 14 in a lug 15 of ring 2, and fitted with a cap 16 of such size that it will not pass through the hole, but will serve to support the ring. Each wire 3 is passed through an eyelet 21 in lip 20, which eyelet serves to guide the wire as it is wound onto the lip. A screw 22 screws through a thickened portion of lip 20, and when tightened up bears against flange 18, thus securing lip 20 in position relatively to the part 9 of the canopy.

When screw 22 is loosened lip 20 may be rotated, thus unwinding wires 3 from the lip adjacent to eyelets 21, extending the wires, and lowering ring 2 and globe 1 from the raised position. When ring 2 is in the lowered position lip 20 may be rotated to change wires 3 from the extended position

and wind them onto lip 20, thus raising ring 2, which may be locked in a raised or in an intermediate position by tightening up screw 22.

8. Space 23 between the two parts 8 and 9 of the canopy serves as a ventilation opening, and spindle 5 may be hollow so that conducting wires may be passed therethrough.

10. The supporting ring includes two parts 24, and 25, hinged together at 26, and fitted with lugs 15. When the globe 1 is in position, ring 2 embraces neck 27 of the globe, and the free ends of the ring are fastened 15 together by screw 28, which passes through the end of part 25, and through plug 29 rigidly secured in the end of part 24. By unscrewing screw 28 and rotating part 25 about hinge 26 globe 1 may be removed from 20 the ring.

The scope of the invention is not confined to the described embodiments thereof, and those embodiments may be varied, for example, in Figure 1 it may be arranged for 25 cover 8 to be rigidly fastened to spindle 5, and for lower part 9 of the canopy to be rotatable. The flexible means may be in one length, being fastened to the drum or the like member near the centre of the length, 30 for instance, by hooks, or by being passed through holes in the drum.

What is claimed is:—

1. A lighting fitting comprising a compact unit including a canopy for covering an opening in the top of an illumination appliance, flexible means, a support for the said appliance connected to the flexible means, and contained within the canopy a member arranged to be rotated by hand in the one or 35 the other direction about the axis of the lighting fitting, and adapted by such rotation to change the flexible means from the extended position to raise the support to the canopy, and to allow the flexible means to extend to lower the support.

2. A lighting fitting comprising a compact unit including a canopy for covering an opening in the top of an illumination appliance, flexible means, a support for the said appliance connected to the flexible means, a locking device for locking the support in position, and contained within the canopy a member arranged to be rotated by hand in the one or the other direction about the axis 50 of the lighting fitting, and adapted by such rotation to change the flexible means from the extended position to raise the support to the canopy, and to allow the flexible means to extend to lower the support.

60. 3. A lighting fitting comprising a compact unit including a canopy for covering an opening in the top of an illumination appliance, flexible means, a support for the said appliance connected to the flexible means, and contained within the canopy a member,

arranged to be rotated by hand in the one or the other direction about the axis of the lighting fitting, and adapted by such rotation to draw the flexible means within the canopy, thereby raising the support to the 70 canopy, and to allow the flexible means to extend to lower the support.

4. A lighting fitting comprising an illumination appliance and a compact unit including a canopy for covering an opening in the top of the appliance, flexible means, a support for the appliance connected to the flexible means and adapted to be attached to the appliance but readily detachable therefrom, and contained within the canopy a member arranged to be rotated by hand in the one or the other direction about the axis of the lighting fitting, and adapted by such rotation to change the flexible means from the extended position to raise the support to 80 the canopy, and to allow the flexible means to extend to lower the support.

5. A lighting fitting comprising an illumination appliance and a compact unit including a canopy for covering an opening in the top of the appliance, flexible means adapted to be connected to the appliance, and contained within the canopy a member, arranged to be rotated by hand in the one or the other direction about the axis of the lighting fitting, and adapted by such rotation to change the flexible means from the extended position to raise the appliance to 90 the canopy and to allow the flexible means to extend to lower the appliance.

6. A lighting fitting comprising a compact unit including a canopy for covering an opening in the top of an illumination appliance, flexible means, a support for the appliance connected to the flexible means, and contained within the canopy near the upper part thereof a drum, arranged to be rotated by hand in the one or the other direction about the axis of the lighting fitting, and adapted by such rotation to change the flexible means from the extended position to raise the support to the canopy, and to allow the flexible means to extend to lower the support, means for guiding the flexible means onto the drum, and a locking device 105 for locking the support in position.

7. A lighting fitting comprising a compact unit including a canopy for covering an opening in the top of an illumination appliance, flexible means adapted to be connected to the appliance, and contained within the canopy and secured to an upper part thereof a drum, arranged to be rotated by hand in the one direction or in the other direction about the axis of the lighting fitting relatively 110 to a lower part of the canopy, and adapted by such rotation to change the flexible means from the extended position to raise the appliance to the canopy, and to allow the flexible means to extend to lower the appliance,

and a locking device for locking the appliance in the raised position.

8. A lighting fitting comprising a compact unit including a canopy for covering an opening in the top of an illumination appliance, a central spindle supporting the canopy, a drum contained within the canopy and mounted on the spindle in such a way as to be rotatable in the one direction or in the other direction by hand, positioning means, a locking nut rotatable on the spindle for cooperating with the positioning means to clamp the drum in position, a support for the appliance, and flexible means connected to the support, and adapted to be wound onto and off the drum to raise the appliance to the canopy, or to lower the appliance.

9. A lighting fitting comprising a compact unit including a canopy for covering an

opening in the top of an illumination appliance, flexible means, a support for the appliance connected to the flexible means, said support including a ring having two parts hinged together at two adjacent ends, and means at the other ends for securing these ends together when the ring is operative, a member contained within the canopy and arranged to be rotated by hand in the one or in the other direction and adapted by such rotation to change the flexible means from the extended position to raise the support to the canopy, and to allow the flexible means to extend to lower the support, and a locking device for locking the support in position.

In testimony whereof I affix my signature.

EDGAR Langley RANDALL.
